UNITED STATES PATENT OFFICE

128,296

DESIGN FOR A BUILDING

Ernest Merrell Ellis, Portland, Oreg.

Application March 25, 1939, Serial No. 83,821

Term of patent 3½ years

To all whom it may concern:

Be it known that I, Ernest Merrell Ellis, a citizen of the United States, residing at Portland, in the county of Multnomah and the State of Oregon, have invented a new, original, and ornamental Design for a Building, of which the following is a specification, reference being had to the accompanying drawing, forming part thereof.

In the drawing:

Fig. 1 is a rear perspective view of a building showing my new design;

Fig. 2 is an end elevational view; and

Fig. 3 is a front elevational view.

I claim:

The ornamental design for a building, as shown.

ERNEST MERRELL ELLIS.
